UNITED STATES PATENT OFFICE.

PETER JOSSERAND, OF JOSSERAND, TEXAS.

ACETYLENE-GAS LAMP.

SPECIFICATION forming part of Letters Patent No. 634,757, dated October 10, 1899.

Application filed April 14, 1899. Serial No. 713,009. (No model.)

To all whom it may concern:

Be it known that I, PETER JOSSERAND, of Jossrand, in the county of Trinity and State of Texas, have invented a new and improved 5 Acetylene-Gas Lamp, of which the following is a full, clear, and exact description.

The object of the invention is to provide a new and improved acetylene-gas lamp which is simple and durable in construction, more 10 especially designed for use as a portable table-lamp, and arranged to insure a uniform, perfect, and brilliant light.

The invention consists of novel features and parts and combinations of the same, as will be 15 fully described hereinafter and then pointed out in the claims.

A practical embodiment of my invention is represented in the accompanying drawings, forming a part of this specification, in which 20 similar characters of reference indicate corresponding parts in all the views.

Figure 1 is a side elevation of the improvement. Fig. 2 is a sectional side elevation of the same, and Fig. 3 is an enlarged sectional 25 side elevation of the self-regulating valve.

The improved acetylene-gas lamp is provided with a suitable base A, on which is set a bowl, forming a generator B and containing the calcium carbid C. On the neck B' of the 30 generator B is screwed a cap D, terminating in an upwardly-extending pipe E, supporting a water-reservoir F, adapted to be filled with water through a filling-cap G, having a suitable vent-pipe H to admit air to the water 35 that the latter may flow to the generator B, as hereinafter more fully described.

The upper end of the pipe E connects with a pipe I, extending centrally through the water-reservoir F to connect at the upper end 40 with the burners J for burning the generated gas to produce the desired light.

From the bottom of the water-reservoir F at one side of the pipe E extends downward a pipe K, bent upwardly at its lower end to 45 connect with the chamber N' of a self-regulating valve N. (Shown in detail in Fig. 3.) The chamber N' is provided with a valve N², adapted to be seated on the end of the pipe K, said valve having a downwardly-extending stem 50 N³, fitting loosely in the opening of the pipe K to insure a proper seating of said valve N². A pipe O leads from the chamber N' a short

distance above the valve N² and extends through the cap D into the generator, preferably at the middle thereof, the lower end O' 55 of the pipe O being contracted to allow but a drop of water to pass out of the pipe at a time.

The top of the valve N² is provided with a stem N⁴, countersunk at its top to receive the pointed lower end P' of a screw-rod P, screwed 60 in a screw-cap N⁵, closing the upper end of the chamber N'. On the outer end of the screw-rod P is arranged a suitable handle P², and on said screw-rod within the chamber N' screws a collar P³, adapted to abut against 65 the under side of the cap N⁵. A coil-spring Q engages with its lower end the valve N² to support the latter, and the upper end of said spring Q is attached to the screw-rod P below the collar P³.

Now when the screw-rod P is screwed downward the valve N² is moved to its seat to disconnect the pipe K from the chamber N'; but when it is desired to use the lamp the screw-rod is screwed outward until the collar P³ 75 abuts against the under side of the cap N⁵ to allow the spring Q to just hold the valve N² loosely to its seat.

In order to fill the generator-bowl with calcium carbid, it is only necessary to unscrew 80 the cap D, and after the desired quantity of calcium carbid is placed in the bowl then the cap is again screwed upon the neck B'. The reservoir F is filled with water through the filling-cap G, and when it is desired to use 85 the lamp the screw-rod P is screwed outward, as above explained, so that the water from the overhead reservoir F can flow through the pipe K against the valve N² and lift the latter off its seat and to allow the water to rise 90 in the chamber N' and finally flow into the pipe O and down the same into the generator B, the water passing in drops from the contracted end O' upon the carbid C to cause a 95 generation of gas. This gas rises in the generator and passes through the cap D and pipe E into the pipe I and to the burners J to produce a steady uniform flame and a very brilliant light.

In case the pressure of gas generated in the 100 generator B overbalances the water-pressure on the valve N² then the latter is forced to its seat by the overbalancing pressure to prevent water from passing from the reservoir

F by way of the regulating-valve N to the generator, so that further generation of gas ceases until the pressure has diminished to such an extent that the water-pressure exceeds the gas-pressure and the valve N² is again opened by the action of the water to admit some water to the generator for generating a new batch of gas.

From the foregoing it is evident that the water passing through the regulating-valve and the pipe O to the generator is effectively regulated to insure a uniform generation of gas, and consequently a uniform flame at the burner J. By reducing the end of the pipe O within the generator B water is admitted but drop by drop to prevent a too-quick generation of gas and a consequent flashing up of the flame at the burner J.

Having thus fully described my invention, I claim as new and desire to secure by Letters Patent—

1. An acetylene-gas lamp, comprising a base, a bowl carried by the base and adapted to contain calcium carbide, said bowl being formed with a screw-threaded neck, a cap screwing on the neck of the bowl and formed with a contracted tubular extension, a reservoir on the upper end of the tubular extension and integral therewith, said reservoir having a central passage extending through it, said passage being of less diameter than the tubular extension and opening into the same a pipe in the said passage and having an open inner end, the outer end of said pipe projecting above the reservoir and provided

with a burner, a water-pipe leading from the bottom of the reservoir, at one side of the tubular extension into the bowl, and a self-regulating valve in the said pipe outside of the lamp substantially as described.

2. In an acetylene-gas lamp, the combination with a generator, and a water-reservoir above the same, of a valve-chamber, a pipe leading from the water-reservoir to the valve-chamber, a spring-supported valve in the said chamber and regulating the admission of water to the chamber, a screw-rod for forcing the valve to its seat, and a pipe leading from the valve-chamber above the entrance of the pipe leading from the reservoir and extending into the generator, substantially as described.

3. In an acetylene-gas lamp, the combination with a generator, and a water-reservoir above the generator, of a valve-chamber, a pipe leading from the water-reservoir to the bottom of the valve-chamber for closing the end of said pipe, a valve in said chamber, a screw-rod engaging the valve-stem, a stop-collar on the screw-rod, a coiled spring surrounding the screw-rod and valve-stem, the spring being secured to the screw-rod and supporting the valve, and a pipe leading from the valve-chamber above the valve to the generator, substantially as described.

PETER JOSSERAND.
